UNITED STATES PATENT OFFICE.

ISAAC S. OHAVER, OF INDIANAPOLIS, INDIANA.

RAILROAD-CROSSING-GATE CONTROL.

Application filed October 30, 1924. Serial No. 746,786.

To all whom it may concern:

Be it known that I, ISAAC S. OHAVER, a citizen of the United States, residing at Indianapolis, in the county of Marion and State of Indiana, have invented certain new and useful Improvements in Railroad-Crossing-Gate Controls, of which the following is a specification.

My invention relates to railroad crossing gate controls, and more particularly to railroad crossing gate controls which are automatically operated by motion of trains or other rolling stock in respect to its direction of travel, and consists substantially in the construction, combination and arrangement of parts hereinafter set forth and pointed out more particularly in the claims.

An object of my invention is to provide a railroad crossing gate which is adapted to be closed by approaching trains or the like, and opened thereby after such trains have passed the crossing. It is a further object of my invention to provide light signals which are adapted to be brought into use simultaneously with the closing of the gates and correspondingly put out of use by the opening of said gates.

It is also an object of my invention to provide a railroad crossing gate control which will respond to the movement of trains or the like, whether they are travelling forwardly or backwardly.

The above and other objects are attained by the structure illustrated in the accompanying drawings, of which: Figure 1 is a diagrammatic representation of my invention as seen from the same view point as a side elevation would be, the line of vision being transverse to the railroad, considered as a whole. Fig. 2 is a reduced fragmentary plan view of my invention, and Fig. 3 and Fig. 4 are detailed fragmentary views, being somewhat enlarged in respect to Fig. 1, and exemplifying certain portions of same, being taken in the proximity of lines 3-3 and 4-4 of Fig. 2.

Similar characters of reference designate similar parts throughout the several views. Referring to Fig. 1, the numeral 1 designates the rails of a conventional railroad, being supported in the usual manner by the ties 2 and secured thereto by means of the pins 3, said ties being in turn supported by the road-bed 4. The cross-sectional position of a typical wagon or automobile road is indi-

cated by the double-dot-and-dash lines 5, in Fig. 1.

The arms 6 and 7 are pivotally supported by the posts 8 and 9, respectively, in a conventional manner, by means of the pivot pins 10 and 11 and the journals 12 and 13, respectively, said arms being thus supported by said posts at a suitable distance from the rails 1, as shown in Fig. 2.

The driven sprocket wheels 14 and 15 are axially secured to the pivot pins 10 and 11 and the arms 6 and 7 are operated by the sprocket chains 16 and 17, respectively, as illustrated in Fig. 3.

The V shaped triggers 18 and 19 are pivotally supported along the railroad, preferably at considerable distance from the crossing, and are adapted to be operated by corresponding trips 20, carried by trains or other rolling stock, said trips being disposed downwardly for the purpose of properly engaging said triggers. In Fig. 1 is fragmentarily shown the front end of a locomotive 21, to which said trips are attached, by means of the bolts 22. Said trips are shown about to operate the trigger 18, the motion of said locomotive being in the direction indicated by the arrow 23.

The pivoted supports for said triggers are formed by means of the trunnions 24 and 25, respectively, which are axially secured to same, and journaled in the bearings 26 and 27, respectively, which are in turn mounted to the upper extremities of the posts 28 and 29, respectively. The driving sprockets 30 and 31 are carried by the trunnions 24 and 25, respectively. Said sprockets are adapted to operate the sprocket chains 32 and 33, respectively, as illustrated in Fig. 4.

On the lower portion of the post 8, beneath the wagon road surface 5, are the idler sprockets 34 and 35 which are both pivotally supported on said post by means of the pivot pin 36, one end of which is fixed to said post. Likewise, the idler wheel 37 is pivotally supported by the pivot pin 38 which is preferably located inwardly of the pin 36 in respect to the invention as a whole, as shown in Fig. 1.

The idler wheels 39 and 40 are pivotally supported by the pivot pin 41 on the lower portion of the post 9 in the same way the idlers 34 and 35 are supported by the pivot pin 36, and the idler wheel 42 is likewise

supported by means of the pivot pin 43 in the same way the pin 38 supports the pulley 37.

5 The wire cable sections 44, 45, 46, and 47 are conveniently provided to connect the sprocket chains 16, 17, 32 and 33, and form with same an endless belt which is threaded in order as stated:

10 Beginning arbitrarily at the sprocket 30 said belt partly surrounds same and the lower strand extends to and embraces the lower side of the idler pulley 34 and, being wrapped about one quarter around, extends to the inner surface of same considering the 15 apparatus as a whole, and extends somewhat vertically to the outer portion of the driven sprocket wheel 14, being wrapped over the top thereof. Said belt extends thence downwardly to the outer portion of the idler pulley 37 and wraps about one quarter around same, extending thence under idler pulley 40 and extending to the upper portion of the driving sprocket 31, being wrapped about half-way around same and extending 20 25 from a lower portion thereof to a lower portion of the idler pulley 39, embracing same about one quarter around and thence extending to the outer portion of the driven sprocket 15, half circumscribing same over 30 the upper portion thereof and extending downwardly to an outer point of the pulley 42 which it circumscribes about one quarter around. Said belt extends thence to a lower 35 point of the idler 35 and thence to the upper portion of the sprocket 30. It will be observed that said belt, being thus threaded, crosses at the point 48, as shown in Fig. 1.

By this arrangement operation of the 40 triggers 18 and 19 aforementioned, will correspondingly operate the gate arms 6 and 7 by means of the above described belt.

45 Referring to Fig. 1, the trip 20 has been carried in the direction of the arrow 23 into contact with the upwardly extending prong 49 of the trigger 18. Continued motion of said trip will move said trigger into the position indicated by the dotted lines 50 of Fig. 1, and the gate arms 6 and 7 will be moved into the position indicated by the 50 dotted lines 51 and 52, respectively, and the trigger 19 will also be oscillated to a position indicated by the dotted lines 53 of Fig. 1.

55 Assuming that said train has passed over the crossing, the trip will embrace the prong indicated by the dotted lines 55, meaning the prong which extends upwardly when the trigger 19 is in the position indicated by the dotted lines 53, and further movement in 60 the direction indicated by the arrow 56, will oscillate said trigger into the position indicated by the solid lines 19 of Fig. 1. The gate arms 6 and 7 will be correspondingly opened and the trigger 18 will be 65 again rotated into the position indicated by

the solid lines 18 of Fig. 1, by which arrangement said triggers are thus automatically adjusted to be embraced by the trips 20 of the next coming train, it being understood that trains moving in either direction 70 will operate the apparatus in the same manner, the finger 57 of the trigger 19 being adapted to be embraced by a trip similar to the trip 20, moved in the opposite direction to that indicated by the arrows 23 and 56. 75

In this particular example of my invention, it is necessary to carry such trips on both sides of the train, because I have provided apparatus similar in construction and symmetrically arranged to the above described gate mechanisms on the other side of the railroad, the members 6^A, 8^A, 10^A, 12^A, 16^A, 18^A, 24^A, 26^A, 28^A, 32^A, 44^A and 47^A being 80 respective to the parts, 6, 8, 10, 12, 16, 18, 24, 26, 28, 32, 44 and 47, and it will be obvious 85 that a train moving, for instance, in the direction indicated by the arrows 23 and 56 of Fig. 1, must carry a trip on each side of the track of the railroad as a whole, in order that the trigger 18^A may be also actuated and thus operate the arms 6^A concurrently 90 with the arms 6 and 7. It is understood that members respective to the above described respective parts are provided (but not shown) in symmetric arrangement 95 thereto, on the other side of the wagon-road 5, but on the same side of the railroad.

Shock absorbing stops 58 are provided to suitably restrict and stop the above described movements of the triggers 18, 18^A, 100 and 19, said stops being secured to the posts 28 and 29 by means of the brackets 59.

The journals 12, 12^A and 13 are secured to the posts 8, 8^A and 9, respectively, by means of the screws 64, and the bearings 26, 26^A, 105 and 27 are secured to the posts 28, 28^A and 29, respectively, by means of the screws 65.

Open spaces indicated by the three dot-and-dash lines 66 of Fig. 1 under the wagon-road 5 are provided to contain and clear the 110 above mentioned idler pulleys and also the underground portions of the above described endless belt means.

The lanterns 60 and 61 are pivotally supported by the arms 6, 6^A and 7, respectively, 115 inwardly in respect to the apparatus as a whole, as shown by Fig. 2, and centrally of said arms as shown by Fig. 1. When said arms are oscillated into the position indicated by the dotted lines 51 and 52 said lanterns will suspend below said arms and will thus serve as a danger signal, it being appropriate to have said lanterns adapted to throw out red light or other suitable colors desired to best carry out the signal purposes. When, however, said arms are in the open or upright position as shown by the solid lines, 6 and 7 in Fig. 1, said lanterns will have been swung on their pivots 62 and 63, respectively, by force of gravity and be 120 125 130

automatically hid behind said arms and thus be hidden from those who might approach the crossing, by which arrangement said lanterns will serve only as a signal during the closed position of the apparatus.

Said lanterns are preferably of the bull's-eye type, in the fact that they throw a light in one direction only, the light outlet of each being directed toward its respective gate, when in the open position of the apparatus. By this arrangement said lanterns will not throw any light in either direction during the upward or open position of said arms; as the arms themselves will shut off the light coming from said outlet.

The above mentioned prongs of the triggers 18 and 19 are arranged in spoke-like manner on the hubs of the respective triggers and may therefore be said to be radially arranged. Said prongs may therefore be compared to gear teeth and the trip would, in that sense, be considered as rack gear tooth, adapted to embrace said arms accordingly.

25 The above mentioned idler pulleys are preferably of the sheave type so that the above described belt means may be more definitely retained on same.

It is obvious that my trigger means 18 and 19 may be operated by trips 20 approaching from either direction. Furthermore, it is immaterial whether said trips are carried on trains moving forwardly or backwardly. This is especially true in view of the fact that I preferably carry such trip means on each side of the trains, by which arrangement there will always be carried a trip on each side of such train regardless of whether such train approaches the apparatus forwardly or backwardly.

40 While I have described a four-gate and trigger apparatus, it is understood that a mechanism when so described may be considered complete in itself, when comprising the apparatus on one side of the railroad only.

45 While I have illustrated in a general way, certain instrumentalities which may be employed in carrying my invention into effect, it is evident that many modifications may be made in the various details, without departing from the scope of the appending claims, it being understood that my invention is not restricted to the particular forms herein described.

50 I claim as my invention:

1. In railroad crossing gate controls, a conventional railroad crossing gate means pivoted adjacent a railroad and wagon-road crossing, on one side of the wagon-road; a trigger means, pivoted on the same side of said wagon-road, having radially arranged prongs; another such gate means arranged on the other side of said wagon-road; an- 55 other such trigger means also arranged on

the other side of said wagon-road; a trip means extending from trains etc. passing along said railroad, and adapted to engage said prongs in rack tooth manner, and oscillate same; a chain belt means adapted to transmit motion from said trigger means to said gate means, said belt means being oppositely wrapped on the respective gate means and trigger means, whereby a train approaching with said trip means in either direction, will close said gate means thru the first engaged trigger means and open same thru the last engaged trigger means; and guide means adapted to guide said belt means.

2. In railroad crossing gate controls, trip means extending downwardly on each side of railroad trains etc. and adapted to be carried thereby; a conventional railroad crossing gate means located adjacent a railroad and wagon-road crossing on one side of the wagon-road, and on one side of the railroad; a trigger means located on the same side of said wagon-road and said railroad and adapted to be operated by the trip means carried on the same respective side of said trains; another such gate means located on the other side of said wagon-road, but on the same side of said railroad; a trigger means also located on the other side of said wagon-road, but on the same side of said railroad and adapted to be operated by the trips carried by said trains on the same respective side of said railroad, a third such gate means located on the other side of said railroad, but on the same side of said wagon-road as the first mentioned gate means; a trigger means also located on the other side of said railroad, but on the same side of said wagon-road, as the first mentioned trigger means and adapted to be operated by the trip means carried by trains on that respective side of said railroad; a fourth such gate means located on the opposite side of said wagon-road from the first mentioned gate means and also on the opposite side of said railroad from the first mentioned gate means; a trigger means located on the opposite side of said wagon-road from the first mentioned trigger means, being also on the opposite side of said railroad from the first mentioned trigger means, said trigger means being adapted to be operated by the trip means carried on that respective side of said railroad; a chain sprocket means adapted to embrace the trigger means and gate means on one side of said railroad whereby operation of said trigger means will close said gate means; another sprocket chain means adapted to embrace the trigger means and gate means on the other side of said railroad; and radially arranged lever means constructed on all of said trigger means adapted to engage said trip means in gear.

105 110 115 120 125 130

tooth manner, whereby such trains in passing, will open said gate means thru the trigger means on the side of the wagon-road first approached and close same thru the trigger means on the other side of the wagon-road.

3. In railroad crossing gate controls, a trip means extending downwardly from and adapted to be carried by railroad trains etc.; a conventional railroad crossing gate means located adjacent a railroad and wagon-road crossing, on one side of the wagon-road; a trigger means located on the same side of said wagon-road adapted to be operated by said trip means; another such gate means located on the other side of said wagon road; a trigger means also located on the other side of said wagon-road; adapted to be operated by said trip means; independent sprocket means axially secured to each of said trigger means and said gate means; and an endless chain belt means adapted to embrace all of said sprocket means in typical working manner, said belt means being crossed between the different sides of said wagon-road, whereby the direction of the gate means and trigger means on one side of the wagon-road will be opposite from the gate means and trigger means on the other side of said road so that trains approaching from either direction will operate the trigger means, which it first embraces, to close said gates while such train is passing.

35 4. In railroad crossing gate controls, a trip means extending downwardly from and adapted to be carried by railroad trains etc., a conventional railroad crossing gate means located adjacent a railroad and wagon-road crossing, on one side of the wagon-road; a trigger means located on the same side of said wagon-road adapted to be operated by said trip means; another such gate means located on the other side of said wagon-road; a trigger means also located on the other side of said wagon-road, adapted to be operated by said trip means; independent sprocket means axially secured to each of said trigger means and said gate means; an endless chain belt means adapted to embrace all of said sprocket means in typical working manner, said belt means being crossed between the different sides of said wagon-road whereby the direction of oscillation of the gate means and trigger means on one side of the wagon-road will be opposite from the gate means and trigger means on the other side of said road so that trains approaching from either direction will operate the trigger means, which it first embraces, to close said gate means while such train is passing; and tunnel means in the wagon-road structure adapted to contain the lower portions of said chain belt means.

5. In railroad crossing gate controls, a trip means extending downwardly from and adapted to be carried by railroad trains etc.; a conventional railroad crossing gate means pivoted adjacent a railroad and wagon-road crossing, on one side of the wagon-road; a trigger means pivoted on the same side of said wagon road adapted to be operated by said trip means; another such gate means pivoted on the other side of said wagon-road; a trigger means also pivoted on the other side of said wagon-road; independent sprocket means axially secured to each of said trigger means and said gate means; an endless chain belt means adapted to embrace all of said sprocket means in typical working manner, said belt means being crossed between the different sides of said wagon-road, whereby the movement of the gate means and trigger means on one side of the wagon-road will be opposite from the gate means and trigger means on the other side of said road, so that trains approaching from either direction will operate the trigger means, which it first embraces, to close said gate means while such train is passing, idler pulley means adapted to guide said chain belt under said wagon-road; and a tunnel means under the surface of said wagon road adapted to contain the cross of said chain belt, and said idler pulley means.

6. In railroad crossing gate controls, a conventional railroad crossing gate means pivoted adjacent a railroad and wagon-road crossing, on one side of the wagon-road; a trigger means, pivoted on the same side of said wagon-road, having two radially arranged prongs; another such gate means arranged on the other side of said wagon-road; another such trigger means also arranged on the other side of said wagon-road; a trip means extending from trains etc. passing along said railroad, and adapted to engage said prongs in rack tooth manner, and oscillate same; and a chain belt means adapted to transmit motion from said trigger means to said gate means, said belt means being oppositely wrapped on the respective gate means and trigger means, whereby a train approaching with said trip means in either direction, will close said gate means thru the first engaged trigger means and open same thru the last engaged trigger means.

7. In railroad crossing gate controls, a trip means extending downwardly on each side of a railroad train or the like and adapted to be carried thereby; a conventional railroad crossing gate means located adjacent a railroad and wagon-road crossing on one side of the wagon road, and on one side of the railroad; a trigger means located on the same side of said wagon-road and said railroad and adapted to be

- operated by the trip means carried on the same respective side of said trains, another such gate means located on the other side of said wagon-road, but on the same side of said railroad; a trigger means also located on the other side of said wagon-road, but on the same side of said railroad and adapted to be operated by the trips carried by said trains on the same respective side of 5 said railroad, a third such gate means located on the other side of said railroad, but on the same side of said wagon-road as the first mentioned gate means; a trigger means also located on the other side of said railroad, but on the same side of said wagon-road, as the first mentioned trigger means and adapted to be operated by the trip means carried by trains on that respective side of said railroad; a fourth such gate 10 means located on the opposite side of said wagon road from the first mentioned gate means and also on the opposite side of said railroad from the first mentioned gate means; a trigger means located on the opposite side of said wagon-road from the first mentioned trigger means, being also on the opposite side of said railroad from the first mentioned trigger means, said trigger means being adapted to be operated by the trip 15 means carried on that respective side of said railroad; a chain sprocket means adapted to embrace the trigger means and gate means on one side of said railroad whereby operation of said trigger means will close 20 said gate means; and another sprocket chain means adapted to embrace the trigger means and gate means on the other side of said railroad, whereby operation of said triggers will close said gate means. 25
8. In railroad crossing gate controls, conventionally pivoted gate arms; chain sprocket means axially secured thereto; trigger means adapted to be actuated by the normal travelling movements of railroad trains etc.; chain sprocket means axially secured to said trigger means; and a continuous belt means adapted to engage both of said sprocket means so that the actuation of said trigger means will correspondingly operate said gate arms; and light means pivoted to said arms, having their light outlets covered by the same in the vertical position thereof, said light means being adapted to be oscillated on their pivots and hang with said outlets below said arms in the horizontal position thereof. 30
9. In railroad crossing gate controls, a conventional railroad crossing gate means pivoted adjacent a railroad and wagon-road crossing, on one side of the wagon-road; a trigger means, pivoted on the same side of said wagon-road, having two radially arranged prongs; another such gate means arranged on the other side of said wagon-road; another such trigger means 35 also arranged on the other side of said wagon-road; a trip means extending from trains etc., passing along said railroad, and adapted to engage said prongs in rack tooth manner, and oscillate same; a chain belt 40 means adapted to transmit motion from said trigger means to said gate means, said belt means being oppositely wrapped on the respective gate means and trigger means, whereby a train approaching with 45 said trip means in either direction will close said gate means thru the first engaged trigger means and open same thru the last engaged trigger means; and light means pivoted to the arms of said gate means and having their light outlets covered by said arms in the open position of same, said outlets being adapted to suspend below said arms by gravity, in the closed position of 50 said arms. 55
10. In railroad crossing gate controls, a trip means extending downwardly on each side of a railroad train or the like, and adapted to be carried thereby; a conventional railroad crossing gate means located 60 adjacent a railroad and wagon-road crossing on one side of the wagon-road, and on one side of the railroad; a trigger means located on the same side of said wagon-road and said railroad and adapted to be 65 operated by the trip means carried on the same respective side of said trains, another such gate means located on the other side of said wagon-road, but on the same side of said railroad, a trigger means also located 70 on the other side of said wagon-road, but on the same side of said railroad and adapted to be operated by the trips carried by said 75 trains on the same respective side of said railroad, a third such gate means located on the other side of said railroad, but on the same side of said wagon-road as the first mentioned gate means; a trigger means also located on the other side of said railroad, but on the same side of said wagon-road, as the first mentioned trigger means and adapted to be operated by the trip means carried by trains on that respective side of said railroad; a fourth such gate means located 80 on the opposite side of said wagon-road from the first mentioned gate means and also on the opposite side of said railroad from the first mentioned gate means; a trigger means located on the opposite side of said wagon-road from the first mentioned trigger means, being also on the opposite side of said railroad from the first mentioned trigger means, said trigger means being adapted to be operated by the trip 85 means carried on that respective side of said railroad; a chain sprocket means adapted to embrace the trigger means and gate means on one side of said railroad whereby operation of said trigger means will close 90 said gate means; and another sprocket chain means adapted to embrace the trigger means and gate means on the other side of said railroad, whereby operation of said triggers will close said gate means. 95
10. In railroad crossing gate controls, a trip means extending downwardly on each side of a railroad train or the like, and adapted to be carried thereby; a conventional railroad crossing gate means located 100 adjacent a railroad and wagon-road crossing on one side of the wagon-road, and on one side of the railroad; a trigger means located on the same side of said wagon-road and said railroad and adapted to be 105 operated by the trip means carried on the same respective side of said trains, another such gate means located on the other side of said wagon-road, but on the same side of said railroad, a trigger means also located on the other side of said wagon-road, but on the same side of said railroad, as the first mentioned trigger means and adapted to be operated by the trip means carried by trains on that respective side of said railroad; a fourth such gate means located 110 on the opposite side of said wagon-road from the first mentioned gate means and also on the opposite side of said railroad from the first mentioned gate means; a trigger means located on the opposite side of said wagon-road from the first mentioned trigger means, being also on the opposite side of said railroad from the first mentioned trigger means, said trigger means being adapted to be operated by the trip means carried by trains on that respective side of said railroad; a chain sprocket means adapted to embrace the trigger means and gate means on one side of said railroad whereby operation of said trigger means will close 115 said gate means; and another sprocket chain means adapted to embrace the trigger means and gate means on the other side of said railroad, whereby operation of said triggers will close said gate means. 120
10. In railroad crossing gate controls, a trip means extending downwardly on each side of a railroad train or the like, and adapted to be carried thereby; a conventional railroad crossing gate means located 125 adjacent a railroad and wagon-road crossing on one side of the wagon-road, and on one side of the railroad; a trigger means located on the opposite side of said wagon-road from the first mentioned trigger means, being also on the opposite side of said railroad from the first mentioned trigger means, said trigger means being adapted to be operated by the trip means carried by trains on that respective side of said railroad; a chain sprocket means adapted to embrace the trigger means and gate means on one side of said railroad whereby operation of said trigger means will close 130 said gate means; and another sprocket chain means

adapted to embrace the trigger means and gate means on the other side of said railroad, whereby operation of said triggers will close said gate means; and light means pivoted to the arms of said gate means and having their light outlets covered by said arms in the vertical position thereof, said light means being adapted to automatically

suspend below said arms in the horizontal position thereof by which said outlets are 10 uncovered.

In testimony whereof, I have hereunto set my hand on this the 20th day of October, 1924, A. D.

ISAAC S. OHAVER.
